UNITED STATES PATENT OFFICE.

JOSEPH H. SEED, OF BROOKLYN, NEW YORK.

HASP-LOCK.

SPECIFICATION forming part of Letters Patent No. 352,206, dated November 9, 1886.

Application filed March 6, 1886. Serial No. 191,284. (No model.)

To all whom it may concern:

Be it known that I, JOSEPH H. SEED, of Brooklyn, in the county of Kings and State of New York, have invented a new and useful Improvement in Hasp-Locks; and I do hereby declare that the following is a full and exact description thereof, reference being had to the accompanying drawings, and to the letters of reference marked thereon, making a part of this specification, in which—

Figure 1 is an elevation in perspective of my improved hasp-lock; Fig. 2, a transverse section of same in line $x-x$, and Fig. 3 a similar section in line $y-y$ of Fig. 1. Fig. 4 is a perspective of the staple when secured by a plate, and Fig. 5 a perspective of a modified form of pivot-bolt.

My invention relates to that class of hasp-locks in which the locking mechanism to engage the staple is carried by and upon the hasp. Heretofore in locks of this description the hasp is made to swing out upon the pivot-bolt which secures it in a plane coincident with the length of said bolt, so as to lift off from the staple in a direction at right angles to the surface of the casing to which the staple is made fast, whereby when the lock is shot it alone bears all strains exerted upon the hasp and lock in any attempts made to force open the door secured thereby. The construction of the hasp in this form of hasp-lock has also been more or less complicated, in order to prevent a removal or loosening of the bolt or screw by which it is fastened.

The object of my invention is to relieve the lock-bolt from strain when the hasp is locked, and to simplify its construction, and thereby reduce its cost.

In the accompanying drawings, A represents the hasp, made in one piece and suitably enlarged, and recessed at its outer end to receive and inclose in the customary manner a lock mechanism of any approved form, not, however, shown in the drawings. A longitudinal recess is formed upon one or both faces of the shank or stem forming the inner end of the hasp. A longitudinal slot, C, is also formed through the bottom of the recess near the inner end of the shank, and the recess is made deep enough to receive and inclose the head of a bolt, B, inserted through the slot, and by which

the hasp is pivoted and secured to the door D. This bolt is formed with an angular shank, e, (see Fig. 3,) to pass through the door, so that it may not turn in its seat therein; or, as an equivalent device, the bolt may be flanged, as shown in Fig. 5, while its outer end, f, immediately below its head, is made cylindrical to serve as a pivotal bearing for the hasp, upon which it may freely swing and turn in a plane parallel with the face of the door. The head of the bolt B is made wide enough to overlap fully the edge of the slot C, and thereby confine the hasp and prevent it from being lifted or swung outwardly from the face of the door while it is left free to turn and swing over the face of the door upon the bolt as a pivotal center.

A transverse recess is formed in the casing at the outer end of the hasp outside the lock confined therein, and the wall of the casing upon one edge of the hasp, near to its extreme outer end, is cut away or slotted, as shown at G, Figs. 1 and 2, to allow the end of the hasp to be swung as it turns upon the bolt B over the end of a staple, H, secured to the casing of the door in line with said opening or slot G. The hasp may be thus carried laterally over the staple, so that the eye of the latter shall be wholly inclosed within the recess in the end of the hasp, as shown in Fig. 2.

The eye of the staple H is made of a rectangular form, as shown in Fig. 2, either upon the end of a threaded stem or screw, H', or upon a plate, L, (see Fig. 4,) by which it is made fast to the door post or casing. An offset or shoulder, i, is formed centrally under the inner bar, j, of the eye proper, whereby when the staple is secured in place an open space or recess is left between the inner member or bar, j, of the staple and the surface of the casing. A plate, k, is secured transversely over the opening of the recess in the outer end of the hasp to project from the edge of the hasp opposite to the slot or opening G inwardly. When the hasp is swung laterally over the eye of the staple so as to inclose it, this plate k is carried under the lower bar, j, of the eye of the staple into the recess between it and the face of the door-casing, as shown in Fig. 2. It thus serves to confine the hasp upon the staple in such manner as to prevent the hasp from being lifted off

from the staple at a right angle to the face of the door and casing, and prevent, in fact, any movement whatever thereof except in the reverse direction to that in which it was swung 5 over the staple; hence when the bolt L of the lock is shot into the eye of the staple the only strain to which it may be subjected is that which may be occasioned by an attempt to swing back the hasp off of the staple by turning 10 it about the bolt B as its pivotal center in a plane parallel with the face of the door. The longitudinal slot C in the stem of the hasp through which the bolt B is passed permits the adjustment of the opening G in the outer end 15 of the hasp, so that it shall register properly with the staple in case of a shrinkage of the door or a change in its relation to the casing in which the staple is secured.

I do not claim, broadly, a hasp bearing a 20 locking mechanism and pivoted to turn upon a bolt and to inclose within the recess in its outer end a staple into which the lock-bolt is shot in order to fasten the hasp; but

I claim as my invention—

25 1. The combination, with a staple, H, and a hasp, A, carrying a lock-case upon its outer end to receive a locking mechanism, and formed with a slot, G, cut in its edge near its outer end to permit the hasp to slide laterally over the 30 end of the staple H, and thereby bring the lat-

ter within a recess in the end of the hasp in position to be engaged by the lock-bolt, of a transverse plate, k, formed or secured across the end of the recess opposite said opening to pass under and engage the lower bar, j, of the 35 eye of the staple when the hasp is closed over said staple, substantially in the manner and for the purpose herein set forth.

2. The combination, with a hasp, A, carrying a lock-case at its outer end to receive a 40 locking mechanism, a recess in the outer end of the lock-case provided with a lateral opening or slot, G, in the edge of the case, and fitted with a transverse plate, k, formed or fitted across the recess at the end opposite said opening, of a staple, H, constructed with a rectangular eye, and an offset, i, under the inner bar, j, of the eye, whereby the transverse plate k may pass under said bar when the staple is inclosed by the recess in the outer end of the 45 hasp, substantially in the manner and for the purpose herein set forth.

In testimony whereof I have signed my name to this specification in the presence of two subscribing witnesses.

JOS. H. SEED.
